HAZEN L. HOYT, OF GREAT NECK, NEW YORK

BARREL

Application filed December 21, 1927. Serial No. 241,477.

This invention relates to knockdown type of barrels and has for its object to cheapen their construction cost. Another object is to strengthen barrels of this type by the provision of improved reinforcing means capable of being quickly and inexpensively applied. A further object is to provide an improved method for constructing barrels of this type especially in joining and aligning the staves, and also for facilitating the application of substantial reinforcing means.

A variety of suggestions have been offered for the construction of barrels and containers capable of being taken apart and compactly bundled for return shipment. The problem of making a rigid construction for this purpose and the problem of providing a cheap construction have heretofore been independent and not satisfactorily reconciled in a single construction. Large scale production results in inaccuracies in fit and attachment of certain of the staves which inaccuracies may become cumulative with the result that unless considerable care is exercised the construction deviates from the intended shape to the detriment of its appearance and strength. When staves are cut by machine or hand it is very hard to make them uniform and each of the exact width and similarly difficult to make each stave straight and beveled in the precise manner so that inaccuracies do not vary the fit of the group of staves about the barrel heads. It has been suggested to nail transverse bands to each stave but the nailing machine operation is not dependable with the result that the barrel must be gone over by hand in order to have the staves well adapted to stay in place against coming loose in handling. Another suggestion involves boring a hole across the stave intermediate of its faces to receive an internal reinforcing band but this was not found satisfactory because only at prohibitive cost could the necessary precision be given the construction if distortions and preliminary strains on the barrel were to be avoided and because the bored hole weakens the stave.

According to this invention the staves are cut preferably from a sheet of wood veneer and are integrally connected to insure their

proper fitting and appearance. Instead of nailing on a reinforcing band such reinforcement is cut into the staves under pressure which is found to be more effective than nailing or similar securing means. Beside the transverse reinforcement, longitudinal reinforcement is provided between each stave to strengthen the barrel against longitudinal thrusts on one stave from being transferred through the thin connecting veneer layer as is likely to happen when the barrel is dropped on a portion of one edge.

Referring to the drawings:

Fig. 1 shows a sheet of veneer after the staves have been cut; 65

Fig. 2 is a rear view of the construction shown in Fig. 1;

Fig. 3 is an end view of the construction shown in Figs. 1 and 2;

Fig. 4 shows the partially completed barrel with portions broken away; 70

Fig. 5 is a bottom view of the barrel of Fig. 4;

Fig. 6 is an enlargement showing the shape of a longitudinal slot between adjacent staves; 75

Fig. 7 is a view corresponding to Fig. 6 after the longitudinal reinforcing means has been inserted in the slot;

Fig. 8 is a view similar to Fig. 7 after the sheet has been flexed;

Fig. 9 is a portion of the longitudinal reinforcing means shown in Figs. 7 and 8;

Fig. 10 is a side view of the device of Fig. 9; 85

Fig. 11 is a detail of the transverse reinforcing means before it has been permanently secured to the staves;

Fig. 12 is a view corresponding to Fig. 11 showing the reinforcing means after it has been cut into the staves; 90

Fig. 13 is a detail of one construction for the longitudinal edges of the end staves of the sheet shown in Fig. 1; 95

Fig. 14 is a view corresponding to Fig. 13 but with these end staves contiguous and in operative position;

Fig. 15 is an interior view along the longitudinal seam of Fig. 14; 100

Fig. 16 shows a construction in which the staves are shaped to interlock;

Fig. 17 is a view corresponding to Fig. 16 but with the stave connecting portions bent;

5 Fig. 18 shows another way of providing the integral longitudinal reinforce or interlock;

Fig. 19 corresponds to Fig. 18 but with the stave connecting portions bent;

10 Fig. 20 is a section on the line 20^a—20^a of Figs. 16 and 18;

Fig. 21 is a section on the line 21^a—21^a of Figs. 17 and 19;

15 Fig. 22 is a detail of a preferred embodiment of this invention showing only a corner of the barrel on a large scale; and

Fig. 23 is a modified view corresponding to Fig. 22.

Fig. 1 shows a sheet of wood veneer 10 of appropriate size having the staves 11 formed 20 between the slots 12. Across the ends of the sheet are cut the transverse grooves 13 for receiving the ends or heads 15 of the barrel. Each slot 12 is cut to substantially the shape shown in Fig. 6 and of a depth preferably

25 exceeding one-half the thickness of the sheet but leaving a thin portion at the base of the slot integrally connecting the staves 11. The outside 14 of the sheet 10 is provided with preferably two or more transverse grooves 18 30 to receive reinforcing bands and these grooves may be cut before or after the slots 12. A longitudinal reinforcing strip of metal 16 is inserted in each slot 12 as shown in Fig. 6 the slot 12 being flattened slightly at the base

35 an amount sufficient to permit insertion of the reinforcing strip. This strip 16 has a series of teeth 17 projecting from opposite faces for the purpose of cutting into the slot walls or staves when the sheet is flexed in bending 40 and securing the same about the barrel head 15. The teeth 17 are shown as being stamped out of the strips 16 although it will be understood that sharpened projections may be formed in other ways.

45 Prior to flexing the sheet 10 reinforcing bands 19 are inserted in the grooves 18 by first transversely bending the band 19 and inserting the same in the groove 18, the groove being narrower than the band so that the 50 band will be arched above the bottom of the groove after the manner shown in Fig. 11. Application of a rolling pressure along the band 19 will cause the edges of this band to spread and cut into the groove walls as shown 55 in Fig. 12. Reinforcing bands 19 are preferably inserted while the sheet is flat although, of course, they may be applied after the sheet has been flexed around one of the heads 15. Inasmuch as these reinforcing bands 19 are 60 not designed to be under the tension of ordinary barrel hoops, no nailing or additional securing means between each stave and the band is necessary except at the end staves of the sheet, but each band is under somewhat

65 of an initial tension. This serves to prevent

the fibrous connection between staves from separating while the sheet is flat and the band reinforces and also safeguards this same fibrous connection from separating during flexure about the teeth 17 as pivots as the teeth cut into the sides of the staves. The bands 19 are not thought sufficient by themselves to protect the barrel against longitudinal stave displacement under end thrust since with the grain extending longitudinally of the staves the edges of the band would tend to split the wood if cut in too deep under heavy pressure. An additional longitudinal reinforcing means is therefore required either in the form of a separate strip 16 or integrally when the stave edges are shaped to interlock as shown in Figs. 16 to 19 inclusive.

70 The side edges of the end staves are preferably notched deep enough to prevent relative longitudinal displacement.

75 As shown in Figs. 1 and 13 to 15 the edges of the end staves are notched at 21 to receive the complementary or unnotched edge portions 20. While the drawing shows these notches as being relatively shallow so that the outer longitudinal edge is substantially straight, nevertheless much deeper notches 80 may be cut causing such to extend into the outer edge of the staves.

85 By way of illustration a sheet of wood veneer is cut to have a thickness of about three-eighths of an inch, the grain being substantially parallel to the staves or slots 12. The slots 12 and the transverse grooves 13 and 18 are preferably machine cut. Grooves 13 of any desired cross-section will provide a better fit if deeper in the center of each stave and shaped to the periphery of the heads 15. This may be done for example by means of a rotary cutter of substantially the same diameter as the heads, the cutter being moved toward and from the longitudinal center of each stave to give the grooves 13 their curved shape or in the usual manner by a crozer machine. After affixing the reinforcing bands 19 and inserting the reinforcing strips 16 90 within each slot 12 the sheet is flexed about a head 15 of the barrel in a manner to substantially close the slots on the reinforcing strips 16, and, securing means such as hoops are then applied to hold the sheet in flexed condition. Any suitable form of securing means may adjustably retain the hoops 22 under the necessary tension. As shown in 95 Fig. 4 a hoop is placed over the barrel adjacent each head 15, the top hoop being placed on the barrel after the head has been inserted. There will be sufficient yield to the construction shown in Fig. 4 to permit the cover to be placed in the groove 13. To increase yield 100 adjacent groove 13 the flexed integral stave connecting portion may be slit by a narrow cutter from the ends to slightly inward of the grooves 13.

105 Instead of the separate reinforcing means 139

of Figs. 7 and 10 inclusive the slots between the staves may be shaped to constitute the functional equivalent and an integral reinforcing means as shown in Figs. 16 to 19 inclusive. In Fig. 16 it will be seen that the slot 12^a between each stave is cut as illustrated to provide interfitting portions or a series of recesses and projections. As shown in Fig. 20 this slot 12^a is substantially straight

10 at its base but the sides of the slot while inclined to each other at the same angle as shown in Fig. 6 are both moved from a position in which one side of the slot is substantially vertical to a position in which the opposite side of the slot is vertical. This shaped slot may be cut by oscillating the cutter axis a limited amount in a substantially vertical plane. Fig. 17 corresponds to Fig. 16 but with the stave connecting portions flexed and the slots closed. Here as before the slots are shaped so as to limit the degree of flexure about the fibrous connection between staves at the base of the slots whenever necessary although the heads may limit such flexure.

20 Instead of having the slots cut in the shape shown in Fig. 16 they may be cut as illustrated in Figs. 18 and 19 by first cutting a narrow slot the width of the base and then chiseling one side of the narrow slot to produce the desired bevel for predetermined distance and then beveling the opposite side of the slot for a corresponding distance. Fig. 19 shows the slots of Fig. 18 in substantially closed position with the sheet flexed. Figs.

30 16 and 17 show the preferred construction because it is cheaper to get the projections to snugly interlock for the transmission of longitudinal thrusts without the expense and precision necessary in accurately forming the interlocking projections of Figs. 18 and 19

40 when the staves are connected in the manner illustrated. Unless the interlocking projections snugly fit to transmit longitudinal thrusts without movement of a stave there is danger that the thin flexed connecting layer of veneer will take a substantial portion of such thrust. In other words, the constructions of Figs. 16 and 17 are better adapted to safeguard the flexed veneer connections

45 between staves against longitudinal thrusts than is the construction of Figs. 18 and 19 without high cost for precision, although the construction of Figs. 18 and 19 may be satisfactory when the staves are not connected by

50 the flexed veneer layer but are only connected through the bands 19. Fig. 21 is a view on the line 21^a—21^a of either of Figs. 17 or 19 or both.

The use of a multi-ply sheet of veneer in forming the barrel is illustrated in Figs. 22 and 23 where the inner ply has the grain running longitudinally of the staves and the outer ply has the grain running around the barrel as illustrated. Fig. 23 has no reinforcing bands 19 since the outer ply there functions

to reinforce the sheet, but in Fig. 22 the sheet reinforcement is obtained both from the outer ply having its grain running around the barrel and also from the band 19. In both these figures the inner edges of the staves have the substantially sinusoidal appearance of Fig. 16 when the sheet is flexed except that in these figures the wave length is somewhat shorter than in Fig. 16.

Among the advantages of this invention may be mentioned the cheapness of production, the accuracy and improved appearance by reason of having the staves all integrally connected. The provision of both the transverse reinforcing bands 19 and the longitudinal reinforcing strips between staves contributes to the rigid and durable construction. The bands 19 are desirable where the sheet is to be flattened out after use for reshipment. In taking down the barrel for reshipment the consumer will find it desirable to leave the reinforcing strips 16 within the slots 12 and secured to the edge of one stave and detached from the opposite edge of the adjacent stave, although if desired these strips may be taken out and separately reshipped. If in taking down the barrels and flattening out the sheets 10 these sheets are stacked there will be small likelihood of the reinforcing strips being slipped out of the ends of the slots. In the modification of Figs. 16 to 21 no separate strips 16 are necessary. While the barrels of this invention may be constructed of a variety of woods it is desirable to make them of the harder woods like birch, maple, or preferably beech. Instead of being formed of a single thickness of veneer, the sheet may be built up of several thicknesses held together in the customary way for plywood. In this last case the grain on the outside of the barrel is preferably transverse of the staves while that inside is longitudinally thereof as in Fig. 1. Multi-ply constructions permit larger and stronger barrels to be made. The outer ply may be considerably thinner than the inner and with its grain transverse of the staves may serve as a reinforce in place of the bands 19. Unlike most of the previous knock-down barrel constructions this invention is well adapted to hold liquids by use of packing between the abutting staves at the ends of the sheet.

I claim:

1. A sheet of material provided with scoring to localize hinge-like flexure, said scoring being so shaped as to limit the degree of the localized flexure and at the same time so shaped as to reinforce the flexed sheet against thrusts longitudinally of the scoring.

2. A sheet of material having a plurality of V-shaped slots when the sheet is not flexed, said slots being of less depth than the sheet in some portions thereof and forming staves, the axes of said slots which project from the sheet being inclined at gradually different

angles between each pair of staves to longitudinally reinforce the staves when the slots are substantially closed.

3. A barrel comprising staves having their inner edges bevelled and substantially sinusoidally serrated and their outer edges of different shape.

4. A container having bevelled staves of fibrous material provided along their inner edges with interlocking and interfitting projections having surfaces which are inclined to the longitudinal stave axis and which are adapted to transmit longitudinal thrusts with a wedging action, the outer stave edges being of different shape from the inner stave edges.

5. A container having bevelled staves connected by flexed stave material, said staves being shaped to limit the hinge-like flexure of the flexed stave material and being shaped along their inner edges to provide interlocking projections having surfaces longitudinally inclined for the transmission of end thrusts between staves.

6. A sheet of material shaped to constitute the sides of a container and provided with slots on the inside extending entirely across the sheet forming flat staves integrally connected at the base of said slots, the inner longitudinal stave edges being longitudinally inclined and forming interlocking projections, the sides of said slots being disposed at an angle to close the slots on the inside of the sheet when flexed and the sides of said slots being spaced at the base of each slot.

7. A container having bevelled staves connected along at least a substantial portion of their longitudinal edges by flexed stave material, said staves being so shaped as to limit flexure and provide, along their inner longitudinal edges interlocking projections of stave material constructed for the direct transmission of a substantial portion of any end thrust between staves to lessen the transmission of such thrusts through the flexed connection.

HAZEN L. HOYT.
